Patented Feb. 17, 1920.

FIG. II.

Inventor
Henry R. Davies

By *Chester A. Braselton*
Attorney.

UNITED STATES PATENT OFFICE.

HENRY R. DAVIES, OF TOLEDO, OHIO, ASSIGNOR TO INDUSTRIAL RESEARCH CORPORATION, OF TOLEDO, OHIO, A CORPORATION OF DELAWARE.

DRIVING MECHANISM.

1,330,848.

Specification of Letters Patent. Patented Feb. 17, 1920.

Application filed July 22, 1918. Serial No. 246,194.

To all whom it may concern:

Be it known that I, HENRY R. DAVIES, a citizen of the United States, residing at Toledo, county of Lucas, and State of Ohio, have invented certain new and useful Improvements in Driving Mechanism, of which I declare the following to be a full, clear, and exact description.

This invention relates to a driving mechanism for use in the starting system of an internal combustion engine. More particularly considered, the invention comprises an automatic screw gearing applicable in the gear train intermediate the electric starting motor and internal combustion engine.

The chief object of this invention is to provide a driving mechanism intermediate the electric motor and engine, which has flexibility and elasticity, and in which there is no spring or similar elastic member in the direct line of power transmission.

Another object is to provide a type of gearing in which the driving connection and disconnection is made in an entirely automatic way.

Another object is to utilize a gearing unit which will automatically take care of variations in engine cylinder compression.

Further objects, and objects relating to economies of manufacture and details of construction will definitely appear from the detailed description to follow.

I accomplish the objects of my invention by the devices described in the following specification. My invention is clearly defined and pointed out in the appended claims.

A device constituting a preferred embodiment of my invention is illustrated in the accompanying drawing, forming a part of this specification in which:

Figure I is a longitudinal section taken through the screw gearing, illustrating the various driving parts in disconnected relation.

Fig. II is a part longitudinal section taken through the resilient portion of the gear, and showing the various parts of the gear in driving relationship; and

Fig. III is a cross section taken on the lines III-III of Fig. II.

In the drawings similar reference characters refer to similar parts throughout the several views, and the section is taken looking in the direction of the small arrows.

Considering the numbered parts of the drawing, I have illustrated an electric motor 1, having a driving shaft 2, with a normal direction of rotation as indicated by the small curved arrow. Upon this driving shaft is a sleeve 3, extending along the greater portion of the exposed part of the shaft, which has a radially extending annular flange 4 at its outer extremity. The inner end of the sleeve is threaded to receive a circular nut 5. The sleeve 3, intermediate the flange 4 and nut 5, is also threaded to approximately half its length. As indicated at 6, a pinion 7 meshes with this thread and is adapted to have longitudinal movement thereon. The pinion 7 is preferably formed with a counterweight 8, though this is not necessary for the effective operation. The pinion in traveling outward along the thread on the sleeve 3, will move into mesh with the gear 9, which in the present application of my invention takes the form of the fly-wheel of the crank shaft.

Forming a buttress to oppose the outward movement of the pinion 7, is a second or external sleeve 10 mounted upon the first-named or internal sleeve 3, so as to have longitudinal movement thereupon. This sleeve 10 has a radially extending flange 11 at its outer end. Intermediate this flange 11 and flange 4 of the sleeve 3, is a compression spring 12, coiled around the sleeve 3. A cup-shaped casing 13 is inserted over the end of the shaft and the spring, and its base is secured to the end of the shaft by means of a screw 14. The inner edge of the casing 13 is threaded to receive an inwardly extending plate 15, which serves as an abutment for the flange 11, thereby limiting the inward movement of the sleeve 10.

Slots are formed in opposite sides of the sleeve 3 as indicated at 16, in which a pin 17, rigidly secured to the shaft of the motor is adapted to have sliding movement. The sleeve 10 serves as a locking means for the pin 17.

For a direction of rotation of the motor shaft as indicated by the curved arrow, the operation of the screw drive is as follows:— Assuming an initial position of the pinion 105 as indicated in Fig. I, the pinion will move outwardly on the screw threads 6, normally meshing with the fly-wheel gear 9. As the pinion moves outwardly, it comes into contact with the external sleeve 10. If the 110

sleeve was fixed immovably upon the internal sleeve 3, the rapid rotation of the shaft would be transmitted with full force to the pinion 7 when it came into contact with the outer sleeve 10, the result of which would be a stripping of the gears and other possible destructive effects. Because, however, of the employment of the spring on the internal sleeve, the sleeve 10 gradually gives under compression incident to the contact of the pinion against its inner edge, so that the transition of the pinion from zero rotation to motor shaft rotation is effected gradually without any serious destructive results.

When the pinion is in contact with the external sleeve and is exerting force thereupon, it is at once evident that there is a tendency to force the internal sleeve inwardly along the shaft, and as the engagement between the sleeve and the shaft permits of a limited movement, the sleeve moves inwardly to a certain extent, limited by the length of the slot 16 in the sleeve. There is thus provided a dual motion of contacting parts when the pinion is in initial engagement with the outer sleeve, so that a flexible and resilient relationship is thereby secured.

The object of utilizing a longitudinal interaction between the motor shaft and sleeve 3 is two-fold. As is well-known in internal combustion engines, resistance offered to rotation of the crank shaft, varies with the point of compression in the various cylinders, so that there is a lack of uniformity in the re-active force of the engine. As this change of re-active force is very rapid, and inasmuch as the pitch of the screw thread upon which the pinion rides is comparatively high, movement of the pinion is not sufficiently rapid to take care of this varying force. Relative motion of shaft and inner sleeve is, however, instantaneous along the slot 16, which easily takes care of this rapid pressure variation.

A second advantage of the slot connection between the shaft and sleeve, is apparent when one considers the effect of the non-enmeshment of the pinion with the fly-wheel gear. If the pinion in traveling outwardly, should engage the gear in such a way that enmeshment was impossible, destructive effects very likely would ensue, unless some means was provided to relieve the jam of the pinion and permit its proper enmeshment. In my device, when the pinion comes in proper contact with the gear-teeth of the fly-wheel, the sleeve 3 immediately begins to move inwardly, the pin 17 traveling along the slot in the sleeve. This movement relieves the pressure intermediate the pinion and gear, and permits a slight rotation of the pinion in the direction of rotation of the motor shaft, which carries the pinion over the point of jam, and permits it, under pres-

sure, to slide into proper position on the gear.

When the engine starts up under its own power, inasmuch as the speed of rotation of the crank shaft greatly exceeds that of the motor shaft, the pinion 7 is moved inwardly along the sleeve and out of mesh with the gear, it being assisted in this action by the spring.

From the above description, it is evident that I have provided a simple and effective driving mechanism which is entirely automatic in its operation, and which takes care of variations in compression in engine cylinders, and the possibility of jamming contact between the pinion and the gear. It is also evident that by utilizing a spring only as a resilient element, and not as a driving connection intermediate the shaft and the gear, I remove to a great extent the possibility of improper performance of the gear, resulting from breakage of the spring.

I am aware that the particular embodiment of my invention herein shown and described, is susceptible of considerable variation without departing from the spirit thereof, and, therefore, I desire to claim the same broadly as well as specifically, as indicated by the appended claims.

Having thus described my invention, what I claim as new and desire to secure by Letters Patent, is:—

1. In a screw gear, the combination of an engine gear; a motor shaft; a sleeve having a threaded portion mounted on said shaft, and adapted to have longitudinal movement relative thereto; an internally threaded pinion mounted on the threaded portion of said sleeve, adapted to have longitudinal movement relative to said sleeve and said shaft into and out of mesh with said engine gear; a second sleeve loosely mounted on, and having movement relative to said first named sleeve; an out-turned flange on one end of said second named sleeve, the opposite end thereof being adapted to be engaged by said pinion; an out-turned flange at one end of the first named sleeve; a compression spring coiled on said first named sleeve, intermediate said flanges; a casing inclosing said spring, having an in-turned end flange adapted to limit movement of the flange of said second sleeve; and means for attaching the casing to the end of the shaft.

2. In a drive mechanism for internal combustion engines, the combination of an internal combustion engine; a gear connected with said engine; a starter shaft; a sleeve for said shaft having an out-turned end flange, and a threaded portion; connections between said sleeve and shaft permitting longitudinal movement therebetween; an internally threaded pinion having screw-

threaded engagement with the threaded portion of said sleeve, and adapted to have longitudinal movement into mesh with said gear; a second sleeve on said first named sleeve, having an out-turned flange, the opposite end of said sleeve being adapted to be engaged by said pinion; a compression spring coiled on the first named sleeve, intermediate the flanges of the sleeves; a casing inclosing the spring, having an end plate adapted to limit movement of the second named sleeve; and means for attaching the casing to the starter shaft.

3. In a drive mechanism for internal combustion engines, the combination of an internal combustion engine; a gear connected to the engine; a starter shaft; a sleeve on said shaft, having limited axial movement relative to the shaft and rotary movement therewith; a second sleeve on said first named sleeve, having limited axial movement relative to the first named sleeve; means for yieldingly holding both sleeves

at one limit of their axial movement; and a pinion threaded on said first named sleeve 25 and adapted to mesh with the gear, said pinion engaging said second sleeve as it moves into mesh with the gear.

4. In a drive mechanism for internal combustion engines, the combination of an internal combustion engine; a gear connected to the engine; a starter shaft; a sleeve on said shaft, having limited axial movement relative to the shaft and rotary movement therewith; a second sleeve on said first 30 named sleeve, having limited axial movement relative to the first named sleeve; single means for yieldingly holding both sleeves at one limit of their axial movement, and a pinion threaded on said first 35 sleeve and adapted to mesh with said gear and having yielding engagement with said second named sleeve.

In testimony whereof, I affix my signature.

HENRY R. DAVIES.
